CARTON TAPING MACHINE WITH STEAM
MOISTENER FOR THE TAPEAlbert F. Shields, Forest Hills, N. Y., assignor to
S & S Corrugated Paper Machinery Co., Inc.,
Brooklyn, N. Y., a corporation of New York

Application December 9, 1947, Serial No. 790,683

5 Claims. (Cl. 216—30)

1

My present invention relates to carton taping machines, and more particularly to devices for automatically taping the seams of paper boxes, cartons, or the like, and is particularly directed to mechanism which will operate on a folded box or carton moving the same into appropriate juxtaposition with the taping mechanism which applies the tape to the seam.

My invention is primarily directed to automatic steam moistening means for the gummed tape which is placed by the machine on the box, the said moistening means applying moisture to the tape as the tape is applied and only to that portion of the tape which is actually applied.

The foregoing and many other objects of my invention will become apparent in the following description and drawings in which:

Figure 1 is a view in perspective of my novel taping device.

Figure 2 is a top plan view taken from line 2—2 of Figure 1, looking in the direction of the arrows, with the cartons removed showing the general arrangement of the various elements of the folded box feeding and guiding means.

Figure 3 is a side view taken from line 3—3 of Figure 2 looking in the direction of the arrows.

Figure 4 is a detailed view of a portion of the mechanism for actuating the switch of the solenoid operated valve for the steam moistener.

Figure 5 is a view in perspective of the steam moistener.

Figure 6 is a circuit diagram for the steam moistener.

Referring now to Figure 1, a control shaft 10 is rotated by sprocket 11 and chain 12 from sprocket 13 on driving shaft 14. Chain 12 is a continuous chain connected and wound around sprockets for all other operating elements of the machine. This makes complex gearing unnecessary and ensures preservation of predetermined driving ratios.

Control shaft 10 carries cam 24 which operates in a manner hereinafter described.

Friction disc 25 is also mounted on control shaft 10 and rotates friction pinion 26 slidably mounted on shaft 31 by means of key 30.

Shaft 31 is fitted with bevel gear 50 which engages with bevel gear 32 of shaft 34. Through pulley 35 and belt 36, shaft 34 turns pulley 37 and shaft 38.

Rotation of shaft 38 causes the rotation of feed pulley 40 and idler pulley 41 at a rate predetermined by the distance of the friction pinion 26 from the center of the friction pulley 25; the greater the distance, the greater the speed.

2

Thus, the strip of tape 43 is fed from the roll of tape 42 at a constant rate. This rate of speed may be adjusted to suit the length of strips to be used by means of the handle 49 having threaded end 51 engaging with the bearing nut 52. Nut 52 alters the center distance between pulleys 25 and 26 along the keyed parts of the shaft 31.

After being unwound from roll 42 by the feed pulleys 40 and 41, tape 43 passes between pulleys 44 and 45 which permit it to form a loop 46. Tape 43 then passes around guide pulley 63 and finally to the feed pulleys 70 and 71.

Tape 43 is of a type well known in the art, usually a paper strip having adhesive material on one side thereof.

Pulleys 70 and 71 perform two functions, namely that of guiding the end of the tape to its proper position at the beginning of the seam to be taped, as well as that of feeding a predetermined length of tape to the seam prior to its being cut off by the cutting apparatus hereinafter described.

Pulley 70 is an idler pulley. Pulley 71 on shaft 72 is rotated by pinion 73 which engages with rack 74. Rack 74 is moved in the direction of the arrow once each revolution of the shaft 10 by means of cam 24 which is brought to bear against the cam follower 76. Spring 75 acts in a direction to oppose the rack motion due to cam 24. Shaft 72 is thus activated to move in an intermittent reciprocating manner to feed the tape under the feed belt.

The principal reason for the ratchet is to permit the tape to run past rollers 71 and 72 when it is pulled by the box. This type of ratchet and pinion arrangement is shown in Patent No. 2,372,780, and hence will serve to feed the longest possible length of tape which may be fed by the device.

Shaft 10 also carries at its outer end cam 80 having the recess 81. A lever 82 is pivotally mounted at 83 above the cam 80 and is biased toward rotation downwardly by the tension spring 81. The downward movement of lever 82 is resisted by cam follower 84 which rides on the surface of the cam 80.

When the shaft 10 is rotated so that the recess 81 of cam surface 80 is opposite the follower 84, then the lever 82 may drop down in response to the pull of tension spring 81.

The end 86 of lever 82 opposite its pivot 83 is pivotally connected at 87 to the link 88 which in turn is operatively connected to the knife bar 90. When lever 82 is pulled down by tension spring 81 at the time that the follower 84 is

opposite the recess 81 of cam 80, it drives the link 88 down, thus driving the cutting knife 90 down to shear the tape against the straight edge 92 (Figure 3). This will occur at the end of the seam in the blank as determined by the adjustment of the knife cam.

Cam 98 may be angularly adjusted on shaft 10 to provide an adjustment for the cut-off point.

The purpose of shaft 100 is to allow only a slight adjustment while running in order to position the front edge of the tape properly on the box.

There may also be a similar shaft, not shown, which moves the pin 83 on the arm 82 which actuates the cut-off knife and thus provides a slight adjustment of the position of the rear edge of the tape on the box.

The prefeeding cam 24 causes the tape to be moved forward just far enough for it to be caught between the box and the delivery roll 94. After the tape is so gripped, it is pulled through by the box itself until it is cut off by the knife.

The prefeeder moves the tape a maximum of about 3½ inches, which is somewhat greater than the distance from the knife to where roll 94 contacts the box. The machine as shown is so arranged that a box 98 inches long can be handled which means that 98 inches of tape can be applied before the cut-off operates.

This type of tape cutting mechanism is shown in Patent No. 2,248,744.

The tape itself in the initial set-up of the machine is threaded past the rollers 70 and 71 up to the knife 90 registering with the edge of a block 92. As the tape is fed downwardly by the rollers 70 and 71, it moves beneath the pressure roller 94 which presses the tape down on the carton seam.

Pressure roller 94 which carries one end of delivery belt 140 is mounted on shaft 94a which is driven by pinions 94b and 94c from the driving shaft 14.

My present invention is directed to the moistening of the tape between the rollers 70 and 71 and the delivery roll 94 and more specifically to the moistening of the tape between the cutting block 92 and the roll 94 so that only that portion of the tape which is to be applied is moistened.

The cutting block 92 is carried on the small steam chest 200, a recess 201 being provided in the steam chest to provide clearance for knife 90. The sloped upper surface 202 of the steam chest 200 over which the tape passes between the knife block 92 and the delivery roll 94 is perforated to permit steam to emerge. The steam chest 200 is supported in appropriate manner just above the box blanks. Pipe 204 with a valve 205 spring biased closed is connected between a source of steam, not shown, and steam chest 200. A solenoid 206, when energized, will open valve 205 to permit steam to enter the steam chest 200 and to emerge through openings in surface 202 to moisten the tape.

A switch 210 which is normally closed is mounted on end 105 of link 102. Extension 104 of rack 74 bears against the operator 211 of switch 210 and opens it. When cam 24 pushes down rack 74 to actuate ratchet wheels 70 and 71 to feed the tape, switch 210 is closed to energize solenoid 206 to open valve 205.

Cam 24 is so curved that it will drive the ratchet down to operate rolls 70 and 71 and will then permit spring 75 to return the ratchet. However, cam 24 has additional curve 24a which will prevent the ratchet extension 104 from re-

turning to open switch 210 until the drop-off point of cam 80 which actuates the knife 90 is reached.

Consequently, the steam reaches the tape while the tape is pulled past the knife until the knife cuts the tape. Only that portion of the tape which is to be cut off and applied is moistened; the remainder stays dry.

This obviates the need for cleaning the ratchet 5 rolls 70 and 71 and prevents deposits of gum on the knife blades and other parts of the machine.

The absence of a moistening roll before the ratchet rolls 70 and 71 also reduces maintenance cost and obviates the necessity for removing portions of the tape after the machine has been idle for some time.

The cartons or boxes 120 are fed at relatively high speed by the high speed feed rollers 121, 121 driven from any suitable power source against the 20 stop 122 (see Figures 1, 2, and 3). The carton 120 which is to be taped is held against the stop 122 by the feed rollers 121 until the stop is lowered. When the stop 122 is lowered in the manner hereinafter described, the carton is fed forward very rapidly to the front guide stop members 125 carried on the parallel chains 126.

Chains 126 are mounted, at the feed end, on sprockets 127 on the driven shaft 128.

The delivery ends of chains 126 are mounted on 30 the idling sprockets 130 which rotate on their shaft 131. The chains 126 do not support the cartons 120 but simply are a means for supporting and moving the moving front guide stops 125.

The cartons or boxes 120, after they pass the stop 122, are fed over the high speed feed rolls 135 driven by shaft 14 and are held against the feed roll 135 by the driven pressure rolls 136. These rolls ensure that the blank 120 will be fed right up to the front guide stops 125.

As the boxes are fed forward, they pass between the belts 140 and 141, the feed ends of which are mounted on rollers 94 and 143, respectively, and the delivery ends of which are mounted on appropriate rollers, not shown.

Either the feed or delivery rollers of the belts 45 140, 141 may be driven in any appropriate manner. Belts 140 and 141 engage both surfaces of the boxes 120 and move them away at appropriate speed. The rolls 143 and feed rollers 135 and 136 are spaced from each other by a distance less than the shortest length of box which is to be fed and taped therebetween, and the box or carton thus to be taped is actually supported between these rolls with the upper surface of chains 126 slightly below the level of the upper surface of roll 135 and slightly below the level of belt 141.

Thus, the chain 126 serves only to support and move the pair of front guide stops 125.

The stop 122 is supported on a pair of links 150, one on each side, passing through an opening in an appropriate stationary guide bracket 151 on the frame of the machine at the upper end thereof, and also through an appropriate stationary guide bracket 153 at the lower end of each thereof.

A compression spring 155 is captured between the lower stationary bracket 153 on each side and a collar 156 on the link 150 on each side, thereby biasing the links 150 upwardly and biasing the stop 122 to the upper stopping position shown in Figure 3.

Link 150 on each side is provided at its lower end with an extension 160 engageable by the 70 75 crank arm 161, once during each revolution of

crank arm 161. Crank arm 161 is mounted on the shaft 162 driven from shaft 10 with a one-to-one speed ratio as shown in Figure 1 by chain 165a connecting sprockets 165 and 164.

The reason shaft 162 is driven from shaft 10 with a one-to-one ratio is because it is necessary to have one taping cycle for one gate opening at all times. The machine is arranged so that the ratio between sprocket 13 and sprocket 11 can be doubled when another stop 125a is added to the chain 126 so as to give equal chain distances between the 125 and 125a. This is done to handle small boxes more rapidly. By running the machine at the same speed we can take twice as many boxes with two stops as with one.

If the gate is driven as I have shown in Figure 1, then no adjustment of the gate speed will be required when changing from one to two stops. To accomplish this, I may use two chain drives between 13 and 11, one having twice the ratio of the other. Then I may clutch in either one as desired and remove or replace stop 125a as the case may be.

As the crank arm 161 rotates in the direction indicated by the arrow, past the extension 160 of link 150, it engages the same and pushes it down, thereby driving links 150 down and pulling down the stop 122.

The length of crank arm 161 is so related to the length of extension 160 that the stop 122 will be held down a sufficient length of time to permit the blank 120 to pass the same. Crank arm 161 in its continued rotation will then release the extension 160, thereby permitting spring 155 to drive the link 150 up, thereby permitting spring 155 to drive the stop up. The same construction is embodied on both sides of the mechanism.

All of the elements of my novel device are integrated mechanically so that the correct feeding of the blank is matched with the correct feeding of the tape and so that the tape is cut off at exactly the right position.

Most boxes and cartons are slotted and arranged as shown at carton 128a of Figure 1, so that flaps 128b and slots 128c are provided, the slots registering with the seam 128d at which the tape is to be applied.

Accordingly, the taping operation cannot begin at the exact leading edge of the carton 120, but rather at the line 120e at which the seam begins.

Likewise, the tape cutting operation should be performed at just the time the trailing end 120f and the seam 120d passes beneath the knife edge 90, so that the tape will terminate at the trailing end 120f of the seam.

The gate 122 and the stop 125 are fixed at all times and require no adjustment. The gate merely retracts when 125 comes around enabling the front edge of the box to engage 125.

The stop 125 in turn times the box correctly for the taping head, i. e., it ensures the same front edge position for all boxes so that the setting readings of the taper will have meaning. The pre-feed is set a certain distance behind the front edge. The cut-off is set another (greater by at least $3\frac{1}{4}''$) distance behind the leading edge.

Accordingly, appropriate markings are placed on the scales for adjustment angularly of cam 24 and knife cam 80 so that the leading edge of the seam of the blank at the base of the flap coincides with the beginning of the tape feed

and the trailing edge of the seam of the blank at the base of the flap coincides with the tape cut-off.

The feed roll speed is somewhat over that of the chain 126 to ensure that the box will catch up to stops 125 and stay against it. My apparatus drops the gate as soon as possible after stops 125 pass so that the box will catch up to stops 125 before stops 125 pass the delivery roll 94.

It will be obvious that the gear ratios between the sprockets 127 which drive the chains 126 and the shaft 162 which drives the crank arms 161 should be so adjusted that the crank arms 161 will rotate once for each complete cycle of the stops 125, so that the crank arms 161 will pull down the stop 122 whenever the front guide stops 125 have reached the exactly proper position.

The box itself then pulls the tape out. The feed rollers 136 and 135 rotate at slightly over the chain speed, but as long as the leading edge of the blank is held by the front guide stops 125, all that these feed rollers do is hold the blank steady against the front guide stops 125.

The belts 140 and 141 move at the speed of the blank 120 until the front guide stops 125 on chains 126 have rotated part way around the sprockets 130 at which time the blank is released from these front guide stops 125 and permitted to move out.

Summarizing, therefore, the blanks are successively fed up to the taping device at high speed where they are stopped at the stop 122. On the release of the stop 122, they are fed at high speed against the front guide stops 125 where they are held steady and in accurate relation by the high speed feed rolls 136 and 135. The movement of stops 125 in the direction indicated by the arrow is at a speed exactly equal

to the speed of the delivery belts, so that the blanks during application of the tape are moved at the exactly appropriate speed for such operation.

By this means, therefore, a combination of speeds is obtained whereby the blanks are fed in at high speed but are held at the appropriate speed for taping during the taping operation.

Side guides, not shown, are provided to align the blank so that its seam will pass under the tape application.

From time to time, adjustment of handle 49 may be necessary to ensure that a proper tape loop 46 is provided. This adjustment need be made, however, only infrequently, whenever a new length of tape is to be applied and sometimes to readjust the tape length slightly during a run.

The distance from stop 122 to blade 90 does not limit the size of the box because stop 122 will be held down by the box as it passes over. This is so because only a spring force moves the gate up. The top of stop 122 has been made flat so that it won't mar the underside of the box when the box rubs over the gate.

Also, the distance from blade 90 to where chain 126 ends off does not limit the box because when the box has gone in between the delivery belts for that distance, i. e., to about over the center of 130, the box is sufficiently well held by the delivery belt to progress further without any leading edge guide.

It will also be clear from an inspection of Figure 1 that the near side of the apparatus (opposite the side thereof which contains the driving elements and tape feeding elements) is completely clear and that, accordingly, blanks of any

width may be passed through the taping device. Also, on the driving side of the apparatus, shaft 14, as well as all the other operating shafts, extend below the blank feeding area and all of the other elements extend above the blank feeding area.

The only limitation on the width of the blank which may be fed is that the distance from the seam in the carton to the folded edge on one side cannot exceed the distance from the center of the delivery roller 94 to the pinions 94b and 94c.

The other side of the carton on the opposite side of the seam may project for any distance outside the apparatus. Accordingly, by this means, an open throat taping machine is provided in which the machine elements may occupy substantially limited floor space while the cartons which are to be taped may extend far outside from one side of the machine when extremely wide cartons are to be taped.

The device is so arranged that folded cartons of a width more than double the entire width of the mechanism may be folded thereby. This is so because in any carton except an exactly square carton the tape seam is nearer one edge than the other.

Thus, it will be seen that my invention contemplates a novel means for feeding blanks at high speed to the taping device, taping the blanks at appropriate taping speed, and removing the blanks from the taping device. Accurate registry is obtained by the gate which aligns the front edge and by moving front guides which hold the blanks in proper angular relation with respect to the taping device.

All of the elements are integrated mechanically so that no mechanical or electrical relays or tripping devices are required.

Only two minor adjustments need be made when changing from runs of one blank to another blank, and these adjustments may be readily calibrated to be made instantaneously.

In the foregoing, I have described my invention solely in connection with a preferred illustrative commercial embodiment thereof. Since many variations and modifications of my invention should now be obvious to those skilled in the art, I prefer to be bound not by the specific disclosure herein contained but only by the appended claims.

I claim:

1. In a taping machine for applying tape to the seam of a folded box blank; a tape supply carrying tape with an adhesive composition adapted to become adherent on the application of moisture thereto; means for feeding tape from said tape supply and applying the same to the box blank; means for cutting said tape after a desired length has been fed; and means for moistening said tape; said tape moistening means comprising a conduit, a steam supply for said conduit; an exit for the steam from said conduit; said steam exit from said conduit being located between said cutting means and the point of application of the tape to the box blank; said tape passing over said steam exit between said knife and the point of application of the tape to said box blank.

2. In a taping machine for applying tape to the seam of a folded box blank; a tape supply carrying tape with an adhesive composition adapted to become adherent on the application of moisture thereto; means for feeding tape from said tape supply and applying the same to the box blank; means for cutting said tape after a desired length has been fed; and means for moist-

tening said tape; said tape moistening means comprising a conduit, a steam supply for said conduit; an exit for the steam from said conduit; said steam exit from said conduit being located between said cutting means and the point of application of the tape to the box blank; said tape passing over said steam exit between said knife and the point of application of the tape to said box blank, and means for controlling the supply of steam to said conduit; said means supplying steam to said conduit when the tape is moving thereover and halting the supply of steam to said conduit when the tape in the machine is stationary.

15 3. In a taping machine for applying tape to the seam of a folded box blank; a tape supply carrying tape with an adhesive composition adapted to become adherent on the application of moisture thereto; means for feeding tape from said tape supply and applying the same to the box blank; means for cutting said tape after a desired length has been fed; and means for moistening said tape; said tape moistening means comprising a conduit, a moisture under pressure for said conduit; an exit for the moisture under pressure from said conduit; said exit for the moisture under pressure from said conduit being located between said cutting means and the point of application of the tape to the box blank; said tape passing over said exit for the moisture under pressure between said knife and the point of application of the tape to said box blank.

4. In a taping machine for applying tape to the seam of a folded box blank; a tape supply carrying tape with an adhesive composition adapted to become adherent on the application of moisture thereto; means for feeding tape from said tape supply and applying the same to the box blank; means for cutting said tape after a desired length has been fed; and means for moistening said tape; said tape moistening means comprising a conduit, a moisture under pressure for said conduit; an exit for the moisture under pressure from said conduit; said exit for the moisture under pressure from said conduit being located between said cutting means and the point of application of the tape to the box blank; said tape passing over said exit for the moisture under pressure between said knife and the point of application of the tape to said box blank, and means for controlling the supply of moisture under pressure to said conduit; said means supplying moisture under pressure to said conduit when the tape is moving thereover and halting the supply of moisture under pressure to said conduit when the tape in the machine is stationary.

5. In a taping machine for applying tape to the seam of a folded box blank; a tape supply carrying tape with an adhesive composition adapted to become adherent on the application of moisture thereto; means for feeding tape from said tape supply and applying the same to the box blank; means for cutting said tape after a desired length has been fed; and means for moistening said tape; said tape moistening means comprising a conduit, a moisture supply for said conduit; an exit for the moisture from said conduit; said moisture exit from said conduit being located between said cutting means and the point of application of the tape to the box blank; said tape passing over said moisture exit between said knife and the point of application of the tape to said box blank, and means for controlling the supply of moisture to said conduit; said means

supplying moisture to said conduit when the tape is moving thereover and halting the supply of moisture to said conduit when the tape in the machine is stationary.

ALBERT F. SHIELDS.
